UNITED STATES PATENT OFFICE.

ABRAHAM J. SYPHER, OF IRON MOUNTAIN, MISSOURI.

ROCK-DRILL.

SPECIFICATION forming part of Letters Patent No. 403,496, dated May 14, 1889.

Application filed November 27, 1888. Serial No. 292,021. (No model.)

To all whom it may concern:

Be it known that I, ABRAHAM J. SYPHER, of Iron Mountain, Missouri, have made a new and useful Improvement in Rock-Drills and 5 Analogous Machines, of which the following is a full, clear, and exact description.

The improvement relates, mainly, to the means for cushioning the cylinder-piston and to the valvular mechanism, substantially as 10 hereinafter described and claimed, aided by the annexed drawings, making part of this specification, in which—

Figure 1 is a central longitudinal section of the improved mechanism on the line 1 1 of 15 Fig. 2, which in turn is a cross-section on the line 2 2 of Fig. 1; Fig. 3, a plan of the cylinder, its head, and also the valve-chest removed; Fig. 4, a section on the line 4 4 of Fig. 5, which in turn is a view similar to that 20 of Fig. 1, but showing the piston in a different position in the cylinder; Fig. 6, another view similar to that of Figs. 1, 5, but showing the piston in a third position in the cylinder; Fig. 7, a view of that face of the valve-chest 25 which is applied to the cylinder, and Fig. 8 a cross-section on the line 8 8 of Fig. 6.

The same letters of reference denote the same parts.

A represents the cylinder; B, the valve-chamber; C, the drill-chuck; D, the piston, and E, Fig. 2, the valve. These, as well as the minor parts of the construction, are shaped and combined in the customary manner, saving as modified or supplemented by the improvement under consideration.

A feature of the improvement is, as stated, the means for cushioning the piston and especially on its instroke.

In Letters Patent No. 348,175, granted me 40 August 24, 1886, for an improvement in steam rock-drills, means for cushioning the piston are shown. In that construction the piston is driven by means of live steam admitted into the ends, alternately, of the cylinder, and 45 to cushion the piston. The inlet for said steam is arranged a certain distance, say about one and one-half inch in an ordinary rock-drill, from the cylinder-head, and between the position of said inlet and the cylinder-head another steam-passage leads into the cylinder. This last-named steam-passage

is a branch leading from the first-named or main steam-passage, and it is provided with a valve which seats toward the steam-supply. A steam space is thus formed at the end of the 55 cylinder in which the live steam, by the movement of the piston past the main inlet, is compressed and a cushion thereby formed for the piston. As long as the steam-pressure within said space is less than the pressure within the 60 steam-passage the valve unseats and live steam enters the space; but as soon as the steam by the movement of the piston is compressed to a degree greater than that of the boiler-pressure the valve seats and the steam within the 65 space is further compressed. To this method of forming the steam-cushion there is this objection: The admission and the retention of the steam within the cushioning-space is controlled by a valvular system separate from 70 the piston, and a long lead has to be given to the main valve. This in turn increases the proportions and weight of the engine, and under some circumstances, as when the valve 75 is slow in its action, the steam is not admitted with sufficient promptness to the cushion-spaces to form the desired cushion.

In the present construction there are the usual steam-passages, F and F', for admitting the steam to and exhausting it from the 80 cylinder, and there is a steam-space, G, for the piston to be cushioned in; but in addition to the passages F F', and entirely distinct therefrom, is another steam-passage, H, through which live steam is delivered into the 85 cushioning-space G, and such delivery is controlled by the piston itself, and as follows: d d' represent recesses formed in the piston-surface and, respectively, toward the ends of the piston. As the piston is making its instroke, the parts being so relatively contrived that portion d² of the piston, which is between the recesses d d', and which is equal in diameter to the bore of the cylinder, does not pass the inlet h to the passage H until the inner 90 end, d³, of the piston is about to cover the outlet f from the passage F, and the recess d to take live steam from the port I, Figs. 1, 5, 7. As soon as the recess d comes opposite the port I and the inlet h, live steam passes 95 from the port I into the recess d, thence into the passage H, and thence through the outlet 100

h' into the steam-cushioning space. The piston continuing to move inward covers the outlet *f* and then the inlet *h*, the outlet *f* being closed by the part *d*³ and the inlet *h* by the part *d*⁴ of the piston. There is now no outlet for the steam which has been admitted into the steam-cushioning space, and the piston continuing to move inward is surely cushioned. The pent-up steam serves to initiate the return of the piston, and live steam is also again admitted through the passage *H*, and the outstroke of the piston is completed by means of the live steam admitted through the outlet *f* into the cylinder. The piston may be similarly cushioned at the end of its outstroke, especially when the improvement is being applied to coal-cutting machines, to which end a passage similar to the passage *H*, a port similar to the port *I*, and the recess *d*' may be used, but respectively suitably arranged to conduct the live steam to the out end of the cylinder on the outstroke of the piston in manner similar to that above described in conducting it to the end of the cylinder. The steam admitted into the cushioning-space is, on the return-stroke of the piston, exhausted through the passage *F*. The passage for admitting the live steam to the recess *d* *d*' of the piston is not controlled by the valve, and it is always open to the main steam-supply; hence whenever steam is passing through the valve-chamber to drive the piston there is a current wholly independent of the valve movement passing to the cylinder to be used in cushioning the piston. This last-named steam-current may be delivered in various ways to the cylinder, and after it has been delivered into the interior of the cylinder and into the space formed by the cylinder-recess *d*, in conjunction with the cylinder-shell, it can be conducted by any suitable passage to the cushioning-space. The most convenient location for the last-named passage *H* is through the cylinder-shell, as shown. The most desirable method of supplying the cushioning-current to the cylinder is through the steam-chest and in connection with the valvular system of the drill, which will now be described.

B represents the valve-chamber. The steam is supplied thereto through the inlet *b* and is exhausted therefrom through the outlet *b*'. The valve *E* is a steam-driven one, and it consists of a stem, *e*, and four disks, *e*' *e*² *e*³ *e*⁴, forming what may be termed a "three-spool" valve, and which in its operation is moved longitudinally to and fro in the valve-chamber, which in turn is arranged crosswise upon the cylinder, substantially as is represented. The seat *E'* of the valve *E* is constructed as follows: In its general outline it is tubular, to receive and to provide for the movement of the valve. The diameter of its end portions, *b*² *b*², and of the intermediate portions or bridges, *b*³ *b*⁴ *b*⁵ *b*⁶, conforms to that of the valve-disks. Between the various bridges and end portions recesses *b*⁷ *b*⁸ *b*⁹ *b*¹⁰ *b*¹¹ are

formed in the seat. The recesses extend, preferably, entirely around the seat, and they communicate, respectively, with the following ports: The middle recess, *b*⁹, connects with the steam-inlet *b*, Figs. 1, 5, and also with the port *b*¹² in the steam-chest. The recesses *b*⁸ *b*¹⁰ communicate, respectively, with the passages *F* *F'*, Fig. 2, and the recesses *b*⁷ *b*¹¹ communicate, respectively, with ports *b*¹³ *b*¹⁴, Fig. 4, which in turn lead to the exhaust-outlet *b*'. The valve is operated as follows: A portion of the live steam which enters through the passages *b* *b*¹², and thence through the port *I* into the recess *d*, passes from said recess into a passage, *K*, Figs. 8, 7, which leads through the cylinder-shell and then through the valve-chamber shell, and finally leads into the end space *b*¹⁵, Fig. 4, at the end of the valve-chamber, where it acts upon the valve and moves it, say, into the position represented in Fig. 2. In this position of the valve the live steam is being delivered through the recess *b*⁸ and passage *F* into the cylinder at one, the in end, thereof, and is being exhausted through the passage *F'* and recesses *b*¹⁰ *b*¹¹ *b*¹⁴ *b*'. As soon as the piston has moved to cause its portion *d*² to cover the passage *K*, the live steam in the end space *b*¹⁵ leaks past the disk *e*' into the recess *b*¹¹ and exhausts therefrom. The piston then continues to move outward, and the recess *d*' is similarly brought into coincidence with the port *I*, as shown in Fig. 6, whereupon a portion of the live steam is delivered through a port, *K'*, to the end space *b*¹⁶ at the opposite end of the valve-chamber, causing the valve to be moved in the opposite direction, and the steam is then exhausted from the cylinder through the passage *F* and recesses *b*⁸ *b*⁷ *b*¹⁴ *b*', and the live steam is delivered into the cylinder through the recess *b*¹⁰ and passage *F'*. The piston now commences its inward stroke, and continues to move inward until its portion *d*², covers the port *I*. The steam in the end space *b*¹⁶ then leaks past the disk *e*⁴ into the recess *b*⁷, and thence is exhausted through the outlet *b*', so at each stroke of the valve *E* the steam which has effected the stroke is removed from the valve-chamber by allowing it to leak past the disk against which it has previously exerted its expansive force. The movements of the cylinder-piston and the valve *E* are relatively so timed that after the valve has been moved in one direction there is an interval of time before the steam acts upon the opposite end of the valve *E*, and it is during the interval that the steam can leak to advantage past the disk confining it. So far as this method of moving the valve and then exhausting the steam used in moving it is concerned, I desire to claim it, irrespective of the special means employed in introducing and exhausting the steam used in driving the cylinder-piston.

So far as cutting off the cushioning-current is concerned, I desire not to be restricted to any particular number or arrangement of re-

cesses in the piston; but I prefer the number and arrangement of recesses shown, as thereby a shorter piston and cylinder can be used, which is desirable in many positions in drilling—such, for instance, as occur in driving entries and in stoping.

In the foregoing description steam is referred to as the motive power. I desire not to be restricted thereto, as other gaseous agents—compressed air, for instance—can be employed to operate this improved mechanism, and hence I wish it to be understood wherever the term "steam" is used in this specification that compressed air or the name of any other suitable gaseous agent can be used in its place.

The steam-chest herein named is that portion of the valve-chamber which for the time being is included between the disks e^2 e^3 of the valve—that is, in the position of the valve as shown in Fig. 2 the steam-chest extends from the bridge b^4 to the bridge b^6 , and when the valve is shifted into its opposite position the steam-chest extends from the bridge b^3 to the bridge b^5 . The steam-chest is thus a shifting one, but always in connection with the live-steam inlet and outlet, for by the time the valve has been shifted to open one of the ports F F' it is in position to close the other of said ports. Those portions of the valve which are respectively beyond the disks e^2 e^3 serve to form the valve into, as I prefer to call it, a "three-spool" valve. The two outer disks, e' e^4 , serve mainly as pistons whereon alternately the live steam acts to effect the throw of the valve. The disks e' e^4 never cover any of the ports; but they, in conjunction with the adjacent disk—that is, the disk e' —with the disk e^2 , and the disk e^4 with the disk e^3 , are alternately utilized in the movement of the valve by being made to convert a portion of the valve-chamber into a port through which the steam is exhausted, and such port, it will be noticed, takes the exhaust-steam not only from the cylinder, but also from the space in the valve-chamber without the outermost disk—namely, the space b^{15} or b^{16} , as the case may be. An important advantage accruing from this method of constructing the valve is that the valve can be much lighter in weight than those valves in use. In the case of the ordinary valve it is difficult to get rid of the leak-steam. In the present instance it has only to leak past a thin disk to reach the exhaust-port.

I claim—

1. A steam rock-drill or analogous machine having a cylinder, A, provided with a cushioning steam-passage, in addition to the passages which lead from the valve-chamber to the cylinder and used for supplying the steam to the cylinder for driving the piston,

said cushioning steam-passage being independent of said other steam-passages, substantially as described.

2. The combination of the valve-chamber, the cylinder, the passages F F', the port I, the passage H, and the piston having the two recesses d d' , substantially as described.

3. The combination of the cylinder A, having the cushioning steam-passage H, as described, and the piston having the two recesses d d' , substantially as and for the purpose described.

4. The combination of the valve-chamber, the port I, the cushioning steam-passage H, as described, and the piston having the two recesses d d' , substantially as described.

5. The combination of the cylinder and the piston, said cylinder having the port I, and the passages K K', and said piston having the recesses d and d' , substantially as and for the purpose described.

6. The combination of the cylinder, the valve-chamber, the valve, and the piston, said cylinder having the port I, said valve-chamber having the valve-seat and the spaces b^{15} b^{16} , said valve having the disks e' e^4 , said piston having the recesses d d' , and said cylinder and valve-chamber together having the ports K K', substantially as described.

7. The combination of the valve-chamber, the valve-seat, the spaces b^{15} b^{16} , the recesses b^7 b^{11} b^{13} b^{14} , the outlet b' , and the valve having the end disks, e' e^4 , substantially as and for the purpose described.

8. The combination of the valve-chamber, the valve-seat, and the valve, said chamber having the inlet b , the exhaust-outlet b' , the live-steam outlet b^{12} , the recesses and spaces b^7 b^8 b^9 b^{10} b^{11} b^{13} b^{14} b^{15} b^{16} , and said valve consisting of the stem and the four disks, substantially as described.

9. The combination of the valve-chamber having the bridges b^3 b^4 b^5 b^6 , with the longitudinally-moving valve having the stem and the disk e^2 e^3 , the steam-inlet b , and the passages F F', substantially as described.

10. The combination of the valve-chamber having the recesses b^7 b^8 b^{10} b^{11} b^{13} b^{14} , the bridges b^4 b^5 , and the outlet b' , with the longitudinally-moving triple-spool valve, and the ports F F', substantially as described.

11. The combination of the valve-chamber having the spaces and recesses b^7 b^8 b^{10} b^{11} b^{13} b^{14} b^{15} b^{16} , the bridges b^4 b^5 , the outlet b' , with the longitudinally-moving triple-spool valve, and the ports F F', substantially as described.

Witness my hand this 10th day of November, 1888.
